FIRE ALARM BOX

Samuel Ayres, Jr., Marblehead, Mass., assignor to The Gamewell Company, Newton Upper Falls, Mass., a corporation of Massachusetts

Application September 17, 1954, Serial No. 32,327

Term of patent 14 years

(Cl. D72—1)

Fig. 1

To all whom it may concern:

Be it known that I, Samuel Ayres, Jr., a citizen of the United States of America, residing in Marblehead, Essex County, Commonwealth of Massachusetts, have invented a new, original, and ornamental Design for Fire Alarm Box, of which the following is a specification, reference being had to the accompanying drawings, forming a part thereof.

Fig. 1 is a front elevational view of a fire alarm box showing my new design;

Fig. 2 is a side elevational view thereof; and

Fig. 3 is a bottom plan view.

The dominant features of my new design are shown in solid lines.

I claim:

The ornamental design for a fire alarm box, substantially as shown and described.
